UNITED STATES PATENT OFFICE.

AUSTIN E. MILLER, OF CHENEY, WASHINGTON.

GATE.

Application filed April 26, 1922. Serial No. 556,694.

To all whom it may concern:

Be it known that I, AUSTIN E. MILLER, a citizen of the United States, residing at Cheney, in the county of Spokane and State of Washington, have invented a new and useful Gate, of which the following is a specification.

This invention aims to provide novel means for operating a gate from a remote point. Another object of the invention is to provide novel means for latching the gate.

It is within the province of the disclosure to improve generally and to enhance the utility of devices of that type to which the invention appertains.

With the above and other objects in view, which will appear as the description proceeds, the invention resides in the combination and arrangement of parts and in the details of construction hereinafter described and claimed, it being understood that, within the scope of what is claimed, changes in the precise embodiment of the invention shown can be made without departing from the spirit of the invention.

In the accompanying drawings:—

Figure 1 shows in elevation, a device constructed in accordance with the invention; Figure 2 is a section on the line 2—2 of Figure 1; Figure 3 is an elevation disclosing one of the supports and attendant parts; Figure 4 is a sectional detail illustrating the latch mechanism; Figure 5 is a sectional elevation wherein the structure shown in Figure 4 is viewed at right angles to the showing of that figure; Figure 6 is a sectional elevation showing the gate in closed position; Figure 7 is a horizontal section taken through one of the supports; Figure 8 is a fragmental elevation showing a modification; and Figure 9 is a top plan of the structure delineated in Figure 8; Figure 10 is a sectional view showing a modified form of the invention.

In carrying out the invention, there is provided a frame 1 including a track 2. A guard 3 is located above the track 2 and includes end portions 5 attached by securing elements 6 to the frame 1. The numeral 4 designates a gate, mounted at 7, preferably through the instrumentality of rollers, to move along the track 2. The gate 4 is provided at one end with a keeper 8, adapted to be received in a seat or opening 9 formed in one end portion of the frame 1, so as to

prevent the gate from swinging outwardly with respect to the frame 1, when the gate is in a closed position.

Supports 10 are located at any desired distance from the frame 1. A shaft 11 is mounted for rocking movement in the supports 10 and in the track 2. Angle brackets 12 are provided, each angle bracket including an arm 14 secured to one of the supports 10, and an arm 15 extended parallel to the shaft 11, the shaft 11 being journaled in the arms 14 of the angle brackets 12. Pinions 16 are secured to the shaft 11 outwardly of the supports 10 and the arms 14 of the angle brackets 12, as shown in Figure 7. Segments 17 are mounted at 18 to swing vertically on the arms 15 of the angle brackets 12. Each segment 17 has a depending arm 19 carrying a handle 20, the handle preferably being pivoted at 21 to the arm, so as to hang in a depending position when not in use, as indicated in Figure 1, the construction being such that animals cannot rub against the handles 20 and operate the gate. Each segment 17 includes a lateral rack 22 meshing with one of the pinions 16 on the shaft 11.

A pinion or segment 23 is carried by the shaft 11 and is located adjacent to the gate 4. The shaft 11 has a limited amount of rotation in the pinion or segment 23. The pinion or segment 23 meshes with a rack 24 constituting a part of the gate 4. A latch 25 is pivoted at 26 to the hub of the pinion 23. A bowed spring 27 is secured at 28 adjacent to one end, to the latch 25, the other end of the spring bearing against a stop 29 on the hub of the pinion 23. The spring 27 tends to swing the free end of the latch 25 downwardly, so that the latch will engage with a keeper 30 projecting laterally from the gate 4. A cam or arm 31 is secured to the shaft 11 and is adapted to cooperate with the latch 25 and with the stop 29 in a way which will be pointed out hereinafter.

In practical operation, the segments 17 may be swung on their pivotal mountings 18, through the instrumentality of the arms 19 and the handles 20, rotation being imparted to the shaft 11 through the racks 22 on the segments 17 and the pinions 16 on the shaft 11.

Passing to Figure 4, suppose that the latch 25 on the segment 23 is engaged with the keeper 30 on the gate 4. The shaft 11

rotates to a slight extent, independently of the segment 23 and during this independent rotation of the shaft, the latch 25 is disengaged from the keeper 30, and is moved to the dotted line position of Figure 4, the gate 4 thus being set free. When continued rotation is imparted to the shaft 11, the arm 31 on the shaft, having disengaged the latch 25 from the keeper 30, imparts rotation to the segment 23, by way of the latch 25, and when the segment 23 is rotated, the segment, cooperating with the rack 24 on the gate 4, slides the gate 4 from the closed position of Figure 2 to the right, into an open position. When reverse rotation is imparted to the shaft 11, the gate is carried back into the closed position of Figure 2 and the latch 25 engages automatically with the keeper 30, as shown in Figures 2 and 4.

It will be understood that any suitable means may be provided for imparting rotation to the shaft 11, the structure shown in Figure 4 being retained. In Figures 8 and 9, parts hereinbefore described have been designated by numerals previously used, with the suffix "a". The shaft 11^a is made much shorter than the shaft 11, the supports 10 and cooperating parts being dispensed with, the shaft 11 being journaled in a side bearing 32 on the track 2^a. The shaft 11^a carries a gear wheel or segment 33, meshing with a pinion 34 on the shaft of an electric motor 35, mounted on one side of the track 2^a, or elsewhere. Conductors 36 of any desired length, lead from the motor 35, switches 37 being interposed in the conductors.

Obviously, by operating the switches 37, the motor 35 may be put into operation, the pinion 34 cooperating with the gear wheel or segment 33 to impart rotation to the shaft 11^a, the gate being opened and closed through the instrumentality of the mechanism hereinbefore described.

Reverting to Figure 4 of the drawings, it will be understood that when the shaft 11 is rotated clockwise, the arm or cam member 31, coacting with the stop 29 imparts rotation to the pinion 23, the pinion coacting with the rack 24 to move the gate 4 to the closed position shown in Figure 2 of the drawings.

In Figure 10, the numeral 50 denotes a support, made of concrete, or otherwise, and provided with a slot 51. A lever 52 is located in the slot 51 and is fulcrumed at one end, as shown at 53 on the support 50. A switch 54 is disposed beneath the lever 52. A roller 55 is journaled on the lever 52.

The free end of the lever 52 is pressed upwardly by a spring 56 interposed between the lever and the support 50. The roller 55 projects slightly above the surface of the highway indicated at 57. A vehicle traversing the highway will pass over the roller 55, depress the lever 52, close the switch 54 and operate the date through the instrumentality of the mechanism shown in Figures 8 and 9.

What is claimed is:—

1. In a device of the class described, a frame; a gate mounted to slide on the frame and having a rack; a shaft supported for rotation; a gear member meshing with the rack, the shaft having limited movement in the gear member; a latch movably mounted on the gear member; a keeper on the gate wherewith the latch engages; and a means operable by the shaft for first disengaging the latch from the keeper and then operating the gear member. 80

2. In a device of the class described, a frame; a gate mounted to slide on the frame and having a rack; a shaft supported for rotation; a gear member meshing with the rack, the shaft having limited rotation in 85 the gear member; a latch movably mounted on the gear member; a stop carried by the gear member; a keeper on the gate wherewith the latch engages; and an arm on the shaft, the arm cooperating with the latch to disengage the latch from the keeper and to move the gate in one direction, the arm cooperating with the stop to move the gate in an opposite direction. 90

3. In a device of the class described, a frame; a gate mounted to slide on the frame and having a rack; a shaft supported for rotation; a gear member meshing with the rack, the shaft having limited rotation in 100 the gear member; a latch mounted pivotally on the gear member; a keeper wherewith the latch engages; a stop on the gear member; a spring connected with the latch and cooperating with the stop to hold the latch detachably engaged with the keeper; and an arm 105 on the shaft, the arm cooperating with the latch to disengage the latch from the keeper and to move the gate in one direction, the arm coacting with the stop to move the gate in an opposite direction. 110

In testimony that I claim the foregoing as my own, I have hereto affixed my signature in the presence of two witnesses.

AUSTIN E. MILLER.

Witnesses:

H. J. RUNNINGS,
Jos. LISSACH.
